(57) CLAIM

The ornamental design for a cane clip, as shown and described.

DESCRIPTION

FIG. 1 is a front right top view of the cane clip;

FIG. 2 is a rear right top view of the cane clip;

FIG. 3 is a top view of the cane clip;

FIG. 4 is a bottom view of the cane clip;

FIG. 5 is a front view of the cane clip;

FIG. 6 is a rear view of the cane clip;

FIG. 7 is a right view of the cane clip; and,

FIG. 8 is a left view of the cane clip.

The ornamental design which is claimed is shown in solid lines in the drawings. The broken lines depict portions of the article that form no part of the claimed design.

1 Claim, 4 Drawing Sheets---
